UNITED STATES PATENT OFFICE.

LOUIS V. ARONSON, OF NEWARK, NEW JERSEY.

DESIGN FOR A CLOCK CASING.

Application filed February 5, 1927. Serial No. 20,631. Term of patent 3½ years.

To all whom it may concern:

Be it known that I, LOUIS V. ARONSON, residing at Newark, in the county of Essex and State of New Jersey, have invented a new, original, and ornamental Design for a Clock Casing, of which the following is a specification, reference being had to the accompanying drawing, forming part thereof, in which—

Figure 1 is a front view of a clock casing, and

Figure 2 a side view, showing my new design.

I claim:

The ornamental design for a clock casing, as shown.

LOUIS V. ARONSON.
